UNITED STATES PATENT OFFICE.

CLARENCE B. HARLOW, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SIGNALING DEVICE.

1,304,968.

Specification of Letters Patent.

Patented May 27, 1919.

Application filed May 7, 1917. Serial No. 167,105.

To all whom it may concern:

Be it known that I, CLARENCE B. HARLOW, a citizen of the United States, residing at Chicago, in the county of Cook and State of Illinois, have invented new and useful Improvements in Signaling Devices, of which the following is a full, clear, concise, and exact description, reference being had to the accompanying drawing, forming a part of this specification.

My invention relates to improvements in electric signaling devices, and particularly to the type of device wherein a vibrating diaphragm is provided, which is vibrated under the influence of an electromagnet.

One of the objects of my invention is to provide a simplified form of device of this character, which may be cheaply and easily made.

My device is particularly adapted for use in mine signaling and like places wherein it is desired to provide a vibratory signal somewhat resembling a buzzer, but having a greater volume of sound and being more rigidly constructed.

For the purpose of disclosing my invention, I have illustrated one embodiment thereof in the accompanying drawings, in which—

Figure 1 is a plan view of a structure embodying my invention with the cover removed, and

Fig. 2 is a longitudinal section taken on the line 2—2 of Fig. 1.

In the embodiment illustrated, I provide a diaphragm 1, which may take the form of a flat circular sheet metal disk provided with an annular up-turned flange 2. This disk has mounted on the rear face thereof a ring 3, which is secured to the diaphragm by means of suitable screws passing through the diaphragm and screwing into the ring. The diaphragm is mounted upon a support 5, which is preferably made of the same material as the diaphragm and, as will be seen from the drawing, is almost as wide as the diaphragm. The support extends across the front face of the diaphragm and the diaphragm is secured thereto by means of four screws 6, which pass through the support, through the diaphragm and screw into the ring 3. The support is provided with downwardly extending legs 7 having laterally extending feet 8 provided with suitable

screwholes 9 through which the fastening screws are passed.

Mounted upon the ring 3 is a pair of bridge pieces 10, which extend from one side of the ring to the other and are secured to the ring by screws 11 passing through in-turned feet 12. These bridge pieces provide a support for an electromagnet which comprises a plurality of triangular laminations 13 laid flatwise upon each other and clamped at their bases between the tops of the bridge pieces 10, suitable screws 14 passing through the bridge pieces and laminations for holding the laminations in position. The legs of the laminations forming the pole-pieces of the magnet extend downwardly and their lower ends are spaced apart from the diaphragm 1. These legs are surrounded by suitable windings 15, the terminals of which are connected to binding-post plates 16. These binding-post plates are mounted upon an insulating support 17, which is secured upon the side of one of the bridge pieces 10 by suitable screws 18 and is spaced apart from the insulating bridge piece by bushings 19 surrounding the screws and interposed between the support and the bridge piece. The binding-post plates 14 carry suitable binding screws 20 to which the leading-in conductors 21 are secured. These conductors are brought in through openings 80 formed in the diaphragm 1 and ring 3 and surrounding these openings are rivets 21 which are provided with annular cup flanges 22 extending upwardly and form receiving cups for waterproofing material which is poured therein and surrounds the leading-in wires 21, thereby preventing the entrance of any moisture through the openings for the leading-in wires.

The diaphragm is vibrated by means of a vibrating reed 23, the free end of which lies beneath the poles of the magnet and the opposite end of which is secured by a clamping plate 24 to the ring 3. The free end of the reed is punched up, as at 25, to form a 100 taper.

Inclosing the operative parts of the device is a cover 26, which telescopes within the annular flange 2 and is forced down against a rubber gasket 27 to form at this point a 105 water-tight joint. This cover is held in position by suitable screws 27^a passing through the cover and engaging internally

threaded sleeves 28, which sleeves are secured upon the ring 3 by means of screws 29.

It will be seen from the above that I produce a simple, readily assembled, cheaply manufactured, signaling device, the operative parts of which are inclosed in a watertight casing, and that the support 5 thereof provides a sound chamber for the diaphragm, the diaphragm being suitably spaced apart from the support by means of washers 30 surrounding the screws 6 and interposed between the support and the diaphragm, the front casing and diaphragm being one and the same piece, and of sufficiently heavy material to repel indefinitely the atmospheric action.

Having thus described my invention, what I claim as new and desire to secure by Letters Patent, is:—

1. In an electric sound-producing device, the combination with a diaphragm, of an electromagnet for causing said diaphragm to vibrate, a cover secured to said diaphragm and forming therewith an inclosing casing for the operative parts of the signal, and a wide, flat support for the signaling device secured across the front face of the diaphragm and spaced apart therefrom to form a sound chamber for the diaphragm.

2. In a sound-producing device, the combination with a diaphragm, of an electromagnet for causing said diaphragm to vibrate, a cover secured to said diaphragm and forming therewith an inclosing casing for the operative parts of the signal, and a wide, flat support having downwardly extending supporting legs and secured across the front face of said diaphragm and spaced apart therefrom to form a sound chamber for said diaphragm.

3. In a sound-producing device, the combination with a diaphragm having an angularly extending annular flange, of an electromagnet for causing said diaphragm to vibrate, a cover telescoping within said flange and forming with the diaphragm a casing for the operative parts of the device, and a wide, flat support for said device extending across the front face of said diaphragm and spaced

apart therefrom to form a sound chamber for said diaphragm.

4. In a sound-producing device, the combination with a diaphragm, of a ring secured to one face of said diaphragm, an electromagnet for causing said diaphragm to vibrate secured to said ring, a cover connected to said diaphragm and forming with the diaphragm an inclosing casing for the operative parts of the device, a wide, flat support extending across the front face of said diaphragm, screws extending through the support, the diaphragm and the ring, for securing said parts together and washers interposed between the diaphragm and the support to space the support apart from the diaphragm to form a sound chamber for said diaphragm.

5. In a sound-producing device, the combination with a diaphragm, of a cover secured to said diaphragm and forming with the diaphragm an inclosing casing for the operative parts of the device, binding-posts mounted within said cover for the leading-in wires of the device, said diaphragm having openings therein for the passage of said leading-in wires, and water-proofing material receiving cups surrounding said openings for receiving the water-proofing material to seal the openings after the conductors have been placed in position.

6. In an electric sound-producing device, the combination with a diaphragm, of a cover secured to said diaphragm and forming with the diaphragm an inclosing casing for the operative parts of the device, binding terminals mounted within said casing, said diaphragm having openings therein for the leading-in wires, and hollow rivets secured in said openings provided with integrally formed annular water-proofing material receiving cups through which the leading-in wires pass.

In witness whereof, I have hereunto subscribed my name.

CLARENCE B. HARLOW.
